(57) **CLAIM**

The ornamental design for a limb protector, as shown and described.

DESCRIPTION

FIG. 1 is a front view of a first embodiment of the limb protector embodying the design;

FIG. 2 is a left-side view thereof;

FIG. 3 is a right-side view thereof;

FIG. 4 is a front view of a second embodiment of the limb protector embodying the design;

FIG. 5 is a left-side view of the second embodiment of the limb protector; and,

FIG. 6 is a right-side view of the second embodiment of the limb protector.

The claim is directed to the raised, generally triangular shape and area within it bounded by the solid line contours defining this shape. The broken line depiction of elements that are part of the environment of the design and the areas within them, other than the raised, generally triangular shape, form no part of the claimed design.
